UNITED STATES PATENT OFFICE

2,480,612

FABRICATED BLOCK FOR WALL CONSTRUCTION

Leslie C. Sherman, Albany, N. Y.

Application April 7, 1947, Serial No. 739,821

3 Claims. (Cl. 20—2)

1

This invention relates to novel and useful improvements in building construction and materials therefor.

An object of this invention is to provide a building construction obviating a considerable amount of the necessary skilled labor employed in conventional methods.

Another object of this invention is to provide a building construction obviating the necessity of many conventional elements such as sheathing, plates, siding, interior wall board, panels, a great majority of the nails, etc.

A further object of this invention is to provide a construction utilizing lumber which would otherwise be discarded or used for some lesser purpose.

A still further object of this invention is to provide a labor-saving, economical building construction having a pleasing internal and exterior appearance.

Ancillary objects and features of novelty shall become apparent to those skilled in the art, in following the description of the illustrated preferred embodiments of the present invention, depicted in the accompanying drawings, wherein:

Figure 1 is a perspective view of a portion of a partially constructed wall, made in accordance with the present invention;

Figure 2 is an end view, partly in section and partly in elevation showing the footing and connecting rods forming part of the present invention;

Figure 3 is an enlarged sectional view showing a method of joining and tying the interior and exterior members by means of a dowel fabrication;

Figure 4 is a plan view, partly broken away showing the construction of corners and partitions formed in accordance with the present invention;

Figure 5 is a detail of fabrication with alternate exterior face; and

Figure 6 is a detail similar to Figure 5, showing the dowel connected interior and exterior members forming part of the present invention.

Referring now in detail to the illustrated preferred embodiments of the present invention, like reference characters are used throughout to indicate similar elements.

Among the ancillary objects of this invention there is the provision of a new form of lumber for constructing interior and exterior members of any type building which will be amply strong, self-insulating, quickly and easily assembled by unskilled labor and the provision of space for

2

hidden plumbing, wiring and other conventional building elements of this nature. In a building construction of the nature described, conventional lumber and certain types of trees formerly considered unsuitable for lumber (and also the use of various lengths of any lumber otherwise unsuitable for building sale) may be fabricated into blocks of any desired lengths.

The outside face of said blocks may be fashioned to imitate logs or various types of standard siding. It is within the purview of this invention to provide blocks to imitate bricks, certain masonry constructions, shingles, logs, etc.

A concrete foundation or footing 10 is poured in a conventional way having a plurality of spaced rods 12 set therein and projecting from the top thereof. These rods may be of any suitable material of construction, preferably metallic. A foundation block 14 may then be provided on the said footing 10 and the first fabricated block laid thereon.

These blocks form the essence of this invention and shall be described at this time in detail. A first course 16 and 20 of said blocks is laid on the bearing block 14 and it is noted from an inspection of Figures 2, 5 and 6 that the outside face 18 of said exterior members may be fashioned to simulate masonry, bricks, siding and the like. It is noted from an inspection of Figure 2, that

the upwardly extending rods 12 are received in the central space between members 16 and 20 thereby forming an effective locking means relative to movement transversely of said rod. The rods 12 extend in said central space allowing limited movement thereby permitting shrinkage without appreciable damage. At this point, vertical spacers 22 are provided between said interior and said exterior members. It is here noted that these spacers not only retain the units or blocks

in the desired location, they also provide an aligning means for constructing a straight and true building construction. As is clearly evident from an inspection of Figure 4, a plurality of said spacers 22 may be joined by some suitable conventional means, preferably nails 24 or the like to form substantial corner and partition aligning means.

In fabrication, suitable tie means are provided between said exterior and interior wall and are preferably in the form of conventional dowels 26. Suitable apertures may be provided in each of the performed building block members to receive said dowels 26. Mitre joints 28 are provided at each corner of the building construction and large corrugated fasteners 33 may be used

therewith as fastening means. These mitre joints are conventional and carry therewith all the advantages derived from such a construction.

There may be provided a finishing strip 30 beneath the outer member of the first course 16 of the exterior wall. The said strip 30 is preferably of a configuration which simulates the same surface 18 as used for the remainder of the said wall construction. Suitable securing means, preferably nails, may be used for the purpose of joining the finishing strip 30 to the bearing block 14 described hereinabove.

The inner faces of said interior members are preferably cut to a smooth surface in order that sanding is all that is necessary to provide a finished wall.

A suitable conventional filler is utilized as a bond between courses. This filler is squeezed out through the joints and also need only be sanded to provide an extremely smooth finished wall.

As set forth hereinabove, an improved building block is provided which may be fabricated at a mill by relatively inexpensive labor. A plurality of these blocks may be assembled at the building site to form a durable, rapidly built, attractive structure.

While there has been described but a single preferred embodiment of the present invention, it is apparent to those skilled in the art that various changes including omissions and additions, changes as to size and shape, could be made herein without departing from the spirit of the invention. Accordingly, limitation is sought only in accordance with the scope of the following claims.

I claim:

1. In a wall structure, a footing having rods extending upwardly, a series of superimposed building blocks having abutting edges bonded together by a filler, each of said blocks consisting of an outer member having a facing finish and an inner longitudinal member, said members having an air space therebetween and being supported on said footing, said rods being disposed in said air space, said rods being of a smaller width than said air space to allow slight lateral displacement of the blocks, and means invisible from the exterior of the blocks and disposed in the air space for retaining the outer and inner members fixed to each other.

2. In a wall structure, a footing having rods extending upwardly, a series of superimposed building blocks having abutting faces bonded together by a filler, each of said blocks consisting of an outer member having a facing finish and an inner longitudinal member, said members having an air space therebetween and being supported on said footing, said rods being disposed in said air space, said rods being of a smaller width than said air space to allow slight lateral displacement of the blocks, and means invisible from the exterior of the blocks and disposed in the air space for retaining the outer and inner members fixed to each other, vertical spacers disposed in said air space, a partition fixed by a rabbeted connection to inner members of the blocks, and a vertical spacer at the end of said partition secured to one of said first-mentioned vertical spacers.
- 10 3. In a wall construction, a footing, rods extending upwardly from said footing, an outer wall made up of superimposed horizontal siding members, an interior wall made up of superposed, horizontal members, said inner and outer walls resting on said footing, vertical spacers disposed between said interior and exterior members maintaining an air space between said walls, said rods being loosely fitted in said air space to allow free contraction and expansion of said walls, dowels extending between said horizontal members and said sliding members, and said dowels being disposed transversely with respect to said spacers and invisible from the exterior of each of said walls.
